UNITED STATES PATENT OFFICE.

JOHN S. LUEDTKE, OF WYKOFF, MINNESOTA.

MATCH-SAFE.

1,114,159.

Specification of Letters Patent.

Patented Oct. 20, 1914.

Application filed March 6, 1914. Serial No. 822,857.

To all whom it may concern:

Be it known that I, JOHN S. LUEDTKE, a citizen of the United States, residing at Wykoff, in the county of Fillmore and State 5 of Minnesota, have invented a new and useful Match-Safe, of which the following is a specification.

My invention is an improved match safe provided with means for delivering matches 10 therefrom one at a time and consists in the construction, combination and arrangement of devices hereinafter described and claimed.

In the accompanying drawing:—Figure 1 is a front elevation of my improved match 15 safe. Fig. 2 is a side elevation of the same and Fig. 3 is a vertical section on the line A—A in Fig. 1.

Referring to the drawing by reference numerals, 1 is the front wall, 2 the side walls 20 and 3 the rear wall of a downwardly reduced or wedge-shaped box having an upward projection of its rear wall with a hole 4 therein adapted to go upon a nail or other peg in a wall on which the box may be suspended.

Extending horizontally through a narrow space between the lower ends of the front and rear wall and journaled in the side walls, is a rock-shaft 5, provided at one 30 end with a crank 6. On said shaft are fixed two nearly semi-circular guards or cams 7, each of which is formed with a notch 8 and in front thereof with a segmentally curved radial arm 9.

The front wall of the box is provided with notches 10 for the arms 9 to swing into except as to their ends which are too long to pass into the notches. The rear wall is provided with shallower notches 12 serving as 35 clearings for the cams 7.

In the operation of the device, when matches 11 are placed in the box, as shown in Fig. 3, and the crank 6 is turned forwardly, the notches 8 will carry one match 45 forward beyond the lower end of the front wall, where the operator can catch it as it rolls down along the then lowered curved arms 9 (see dotted lines 9 in Fig. 3). During this part of the operation the curves of 50 the cams support the supply of matches and prevent accidental escape of any part there-

of; when the crank is returned to the normal position the arms 9 exert a lifting, stirring and pressing action on the lower part of the supply of matches, whereby the lowest matches are brought to exact parallel position to the rear wall and thereby caused to drop only one match at a time downward into the notches 8 the moment the supply is released from said rearward pressure by 60 starting the crank and the arms 9 in the forward direction again. It will thus be seen that by using only two resting points, namely in the notches 8 for the match to be delivered, and the curved arms to press said 65 match against the rear wall of the box and crowd the adjacent matches upward, I obviate the usual trouble in match-delivering safes, that the matches will cross each other or be slightly crooked and thereby tangle 70 and clog the delivering mechanism.

What is claimed is:—

1. A match safe comprising a downwardly reduced or wedge-shaped box adapted to be suspended and having in its lower end a 75 narrow slot between the ends of the front and the rear walls, said lower edge of the front wall having two deep notches, a shaft journaled in the side walls of the box and extending along the slot and having at one end 80 a crank, two half-moon shaped cams fixed on the shaft one in line with each notch in the front wall; said cams having each an arm arranged to swing in one of the notches and curved rearwardly intermediate its ends 85 so as to almost reach the rear wall of the box without getting its free end into the notch, said cams having also each a match-carrying notch close by the rear side of each radial arm. 90

2. A match safe comprising a downwardly reduced or wedge-shaped box adapted to be suspended and having in its lower end a narrow slot between the ends of the front and the rear walls, said lower edge of the front 95 wall having two deep notches, a shaft journaled in the side walls of the box and extending along the slot and having at one end a crank, two half-moon shaped cams fixed on the shaft one in line with each notch in the front wall; said cams having each an arm arranged to swing in one of the 100

notches and curved rearwardly intermediate its ends so as to almost reach the rear wall of the box without getting its free end into the notch, said cams having also each a match-carrying notch close by the rear side of each radial arm, said rear wall having clearings for the rear portions of the cams.

In testimony whereof I affix my signature, in presence of two witnesses.

JOHN S. LUEDTKE.
